CLAIM

I claim the ornamental design for a decorative pot holder, as shown and described.

DESCRIPTION

FIG. 1 is a perspective view of a decorative pot holder; FIG. 2 is a front view thereof; FIG. 3 is a rear view thereof; FIG. 4 is a right side view thereof; FIG. 5 is a left side view thereof; FIG. 6 is a top view thereof; FIG. 7 is a bottom view thereof; and, FIG. 8 is a perspective view thereof, shown in an environment of use. The broken lines depict environmental subject matter only and form no part of the claimed design.
